METHOD OF RECONDITIONING DRILL BITS

Ralph E. Calhoun, Metaline Falls, Wash.

Original application April 29, 1941, Serial No. 390,947. Divided and this application February 6, 1942, Serial No. 429,758.

4 Claims. (Cl. 76—108)

This invention relates to improvements in a method of reconditioning drill bits.

It is well known by those who engage in the construction and maintenance of mine tunnels or in any operation of an engineering nature employing the drilling of holes in the earth or rock for the purpose of blasting, that the reconditioning of the worn or dulled bits of the drills presents a problem that in some respects has never been satisfactorily solved.

With the advent of the detachable bit, which has largely replaced the conventional steel of former use, the need for adequate and easily operated reconditioning mechanism has grown very acute.

A drill bit, which ordinarily has from two to four teeth or wings, when it is used loses height due to the dulling or flattening of the cutting edges of the teeth. In addition, it also loses size in gauge diameter due to the undercut nature of the end of a sharpened bit tooth to provide adequate clearance for the rearward passage of dust and the like from the cutting face of the hole being drilled.

The gauge corners of the bit are worn away and consequently the width of the bit is materially reduced from its original size. In order to get the maximum number of usages from such a bit, it is necessary that the original gauge diameter be regained during the reconditioning operation. Otherwise, the loss of this gauge diameter will limit the use of the bit in subsequent drilling operations to those of less diameter where such reduced size bit may be used.

Due to the temper that is given the metal of the bit in order to make it as durable as possible during drilling operations, the reconditioning of the bit by grinding is generally unsatisfactory. Of recent years the heating of the bit and their reconditioning while in a hot malleable condition is being practiced by other methods.

The method disclosed herein is intended to teach a new practice of resizing the bit to a diameter which, when it is subsequently ground and regauged, will be approximately the same as the original gauge diameter before its initial usage.

An important object of my invention has been the provision of a novel method of reconditioning dulled drill bits so that they may subsequently be regauged to a greater diameter than when dull.

Another object of my invention has been the provision of extremely simple, easily operated, durable shaping means for reconditioning dulled rock drill bits.

A further object of my invention relates to the provision of tools whereby the tooth of a dulled drill bit may be fullered or swaged to a desired size without distorting the shape of the tool or otherwise destroying its usefulness.

Still another object of the invention has been the provision of an improved anvil means for receiving and holding the bit during the reshaping operation, in which anvil the bit may be readily indexed to present sequentially the various wings or cutting teeth on the face of the bit to be reshaped.

A still further object relates to the provision of a bit tooth swaging bar having fullering wings, which bar may be associated with a vertically reciprocating means for bringing it easily into and out of engagement with a bit tooth presented to it for reshaping.

Another object of the invention is to provide an improved bit sharpening mechanism, whereby the work may be quickly performed with a minimum amount of manipulation and resultantly extremely low cost for the individual operations.

Yet another object of the invention is to provide improved means for positioning a drill bit for resharpening and for supporting it while the pressure of swaging mechanism is being applied for the resharpening operations, which means is simple of construction and maintenance to effect low initial and operating costs.

Other objects and advantages of the invention will be more apparent during the course of the following description wherein I have described my novel method and illustrated a preferred form of the mechanism by which I practice my method. It will be understood that while I have shown this mechanism having specific form and operation I do not intend to limit the scope of my invention beyond the definitions of the subjoined claims.

In the drawing:

Figure 1 is a view in elevation of a drill bit that has been dulled and in connection with which is shown, in a magnified portion of the drawing, the original contour as well as the resharpened contour that results from the practice of my method in reconditioning such a drill bit.

Figure 2 is an assembly view of the swage bar and anvil mechanism of my invention showing in connection therewith a drill bit as it would appear when presented for reconditioning.

Figure 3 is an enlarged view of a swage bar of Figure 2 with portions broken away for convenience of illustration;

Figure 4 is a plan view of the swage bar as though looking at its bottom face.

Figure 5 is a perspective view of the anvil in which is positioned a drill bit to be reconditioned, and

Figure 6 is a side view of the anvil of Figure 5 with portions broken away for convenience of illustration.

Referring to the drawing, throughout which like reference characters indicate like parts, 10 designates a drill bit having a skirt 12 and a plurality of bit teeth 14, 16 and 18. The skirt 12 is drilled and threaded at 20 for attachment to the conventional drilling bar that is designed for use with the detachable bits of this nature. The usual water hole through the axial center of the bit is indicated at 22.

While I have shown in my drawing and am describing a detachable drill bit it will be understood that the practice of my method and the use of my mechanism is not limited to such devices. In the case of conventional steel where-in the drill teeth are formed on the end of a regular drill shank, the same may also be sharpened as is described herein.

In the magnified portion of the drawing of Figure 1, I have indicated in dashed line and also labelled (1) the original contour of the bit; in solid line, (2) the contour of the dulled bit; and finally in a second dashed line lying in a lower plane, (3) the resharpened contour of the bit after employing the method of my invention. Also indicated in the encircled magnified portion of the bit is the "gauge loss" between the original sharpening of the bit and its dulled diameter as well as the gauge diameter that is regained when the bit is gauged after the practice of my invention.

Upon a suitable base 24 I mount the anvil base plate 26 having thereon the anvil 28. The upper surface 30 of the anvil merges with the inner surface 32 of the bit saddle 34 which is curved and flared adjacent the saddle as indicated by the numeral 36. A drill bit, as 10, is positioned in the saddle so that the flared outer undercut portion of the drill bit wing, i. e., the heel of the bit tooth, rests on the curved portion 36 and also against the anvil face 30.

In the case of detachable bits, a bit shank or handle 38 is inserted into the opening 30 of the bit and is used for manually handling the bit and indexing it during the shaping operation on the anvil.

Upon a vertically movable reciprocable head 40 I mount the attaching plate 42 of the swage bar 44. Bar 44 may be substantially rectangular in cross-section and should be formed of durable stock for long use in shaping the drill bit teeth.

In a lower corner of the bar 44 I form a V-shaped groove 46 which has the flared fullering wings 48, 48 extending therefrom. The wings may be provided with teeth as 49 or under certain circumstances, may be perfectly smooth. The curved surfaces 48 are designed for vertical travel to contact the sloping sides of the bit teeth on either side of the cutting edge to be formed and to press the sides of the bit tooth toward each other to force the metal downwardly and radially outward of the bit to increase the length of the material in which is formed the cutting edge of the tooth. The force of the swage bar is against the bit tooth primarily but it is transmitted to the anvil so that only slightly is it carried on the bit shank. An operator grasping the

shank in his hand has little difficulty in holding the bit on the anvil.

Either the pressure downwardly of the swage bar may be slow and gradual or it may consist of a series of rapid blows such as are used in forging operations wherein the forging tool is moved mechanically with speed.

In practicing the method the bit 10 is heated to a malleable state and so that it is somewhat annealed to remove to a degree temper in the metal. While the bit is in such a malleable state and hot it is affixed to the bit shank 38 and is presented to the anvil so that the heel of a tooth or wing rests on the surface 30 in the path of the swaging bar. The swage bar is lowered producing an opposed fullering action simultaneously on both sides of the metal forming the wing and to swage it outwardly along the axis of the tooth to increase the overall diameter of the bit stock on its cutting face.

The shaping of the remaining bit teeth is performed sequentially one tooth after another. To perform these operations the operator or tool handler merely indexes the bit, one-quarter or one-half of a turn in the case of a four-tooth bit, to present the next tooth to the fullering wings of the swage bar. When all of the teeth of the bit have been reshaped as has been described, the bit is next presented to a conventional grinding tool for smoothing the sloping faces of the bit teeth and also to a gauging grinder for accurately circumscribing the gauge diameter of the bit.

In a subsequent operation the sharpened bit 35 is accurately heated and retempered in the usual manner preferably by the liquid quench method to the desired degree of hardness. It has been found possible to sharpen, by the use of the mechanism shown herein and the method described in 40 this specification, as many as six hundred or over bits a day, with but a single operator handling the mechanism and performing the operation.

In sharpening certain types of drill bits the metal of the drill bit is such that a smooth-faced 45 fullering wing is not practical to use. In that case teeth 49 are provided on the two sides of the V-groove or curved faces of the wing so that they will grab or engage the hot metal of the bit tooth and draw it downward and outward along the axis of the cutter tooth to force the metal to the outer end thereof.

It is an important result of this invention, as it will be noted from the foregoing specification, that my machine is especially designed for the 55 forming of the cutting surfaces of the rock drill bit at extremely high speed in an operation that can be efficient and economical whether performed on a large scale or on a relatively small scale.

It will be further noted that by causing the swage bar with its fullering wings to travel at a relatively high speed in its reciprocating motion and by heating the bit to a safe degree above the critical temperature prior to the forming 65 operation, that the forming of the cutting surfaces of the bit is greatly facilitated, and that the wear of the cutters is thus greatly decreased.

It should also be evident that by the exercise of only a reasonable degree of efficiency by an 70 operator in handling the tool bar to which is attached the drill bit being sharpened that the forming process can be carried on at a speed greatly increased over that of the conventional forging machine and over the grinding wheel 75 method of sharpening drill bits.

Other uses and advantages of the improved machine and of my method will be clearly apparent to those skilled in the art. It will be understood that these forms of the invention are shown for purposes of illustration and that, of course, the invention may be modified and embodied in various other forms without departing from the spirit or scope of the claims.

While I have described a series of steps which constitute the preferred form of practicing my method, it will be apparent that the method may be carried out by varying the manner in which the steps are performed or by performing the steps in a varying order.

Also the apparatus described for carrying out my method is to be understood to be exemplary and may be altered broadly as well as in specific detail to meet altered conditions. In certain cases it will be obvious that other apparatus may be substituted without departing from the principles of the invention.

With regard to the method described, the swage bar need not necessarily be moved but may remain fixed in which case the anvil and bit supported thereon will be moved toward and away from the immovable swage bar. On the other hand, the swage bar and anvil may both be moved toward and away from each other at the same time or at different times. In either of these cases the operation of the swage means upon a bit tooth is unchanged from the others, the principal point being to press the sides of a bit tooth that is properly supported towards each other whereby a motion is set up in the metal of the tooth and the cutting edge of the tooth is swaged radially outward from the axis of the bit.

As to the order in which each of the teeth is sharpened, they need not be forged one after the other around the bit. It can be seen that first one tooth may be swaged or forged, the bit be indexed 180 degrees to present the diametrically opposite tooth and the swaging step then performed thereupon. In such a schedule, the intermediate teeth would be later presented to the swaging means as desired and swaged as presented. Occasionally such a pattern may be suitable for the purposes of relieving strain or unnatural internal stresses, or for improving the grain structure in the metal of the bit.

An important point to be understood about my invention and more particularly about the relative movement between the swage means and the backing-up means is that the movement should be performed with force. Which of the elements is to be moved depends upon the mechanism to be used to impart motion and to the cir-

cumstances surrounding the performance of my method.

While the direction of movement has been described as vertical it will be obvious that the direction may be in any other plane so long as the pressure is applied to the sides of a backed-up tooth and they are pressed together.

Having thus described my invention, I claim:

1. The method of reconditioning a tooth of a worn rock drill bit which method comprises: supporting the heel of the bit tooth to be sharpened, and striking the sides of the bit tooth toward each other but away from the axis of the bit while simultaneously wiping the metal of the tooth into a sharp cutting edge whereby the bit tooth is not only sharpened but motion is set up to swage the tooth metal radially outward of the bit axis.

2. The method of reconditioning worn multi-toothed rock drill bits which method comprises: heating the bit to a forging temperature, positioning the bit so that the heel of the tooth to be sharpened is supported, pressing the sides of the bit tooth toward the supported heel whereby to swage the metal of the bit tooth radially of the bit axis, next serially indexing the bit to sequentially present and support the remaining bit teeth and producing cutting edges thereon as aforescribed, and finally cutting the swaged bit to gauge diameter.

3. The method of reconditioning worn multi-toothed rock drill bits which comprises heating the bit to a forging temperature, positioning the bit so that the heel of a bit tooth is supported, and striking the sides of the bit tooth toward each other but away from the axis of the bit while simultaneously wiping the metal of the tooth into a sharp cutting edge whereby the bit tooth is not only sharpened but is swaged radially outward of the bit axis, next serially indexing the bit to sequentially present and support the remaining bit teeth and pressing as aforescribed.

4. The method of reconditioning a tooth of a dulled drill bit, which method comprises: supporting the heel of the bit to be sharpened, and striking the sides of the bit tooth toward each other rearward of the bit obliquely of the axis thereof while simultaneously wiping the metal of the tooth toward the cutting edge-portion whereby a motion is set up in the tooth metal and the tooth is swaged radial of the bit axis and a new cutting edge on the tooth is simultaneously formed.

RALPH E. CALHOUN.
